US0D1094375S

(12) **United States Design Patent** (10) **Patent No.:** **US D1,094,375 S**
(45) **Date of Patent:** **** Sep. 23, 2025**

(54) **DISPLAY**

(71) Applicant: **SONY GROUP CORPORATION**,
Tokyo (JP)

(72) Inventors: **Sai Karasawa**, Tokyo (JP); **Hiroaki Yokota**, Tokyo (JP)

(73) Assignee: **SONY GROUP CORPORATION**,
Tokyo (JP)

(**) Term: **15 Years**

(21) Appl. No.: **29/853,621**

(22) Filed: **Sep. 16, 2022**

(30) **Foreign Application Priority Data**

Mar. 16, 2022 (JP) ..... 2022-005395 D

(51) **LOC (15) Cl.** **14-02**

(52) **U.S. Cl.**

USPC **D14/375**; D14/447

(58) **Field of Classification Search**

CLAIM

The ornamental design for a display as shown and described.

DESCRIPTION

FIG. 1 is a front, top, left perspective view of a display showing our new design;

FIG. 2 is a rear, bottom, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrating the display or the portions thereof form no part of the claimed design. The dot-dash broken lines defining boundaries of the claimed design form no part of the claimed design.

1 Claim, 8 Drawing Sheets
